UNITED STATES PATENT OFFICE.

HERMANN F. CUNTZ, OF HARTFORD, CONNECTICUT.

TOY.

1,233,320.

Specification of Letters Patent. Patented July 17, 1917.

Application filed December 16, 1908, Serial No. 467,770. Renewed December 9, 1916. Serial No. 136,091.

To all whom it may concern:

Be it known that I, HERMANN F. CUNTZ, a citizen of the United States, resident of Hartford, county of Hartford, State of Connecticut, have invented new and useful Improvements in Toys, of which the following is a specification, reference being had to the accompanying drawings.

My invention relates to a class of toys which can be best described as miniature automobiles and includes self-propelled cars intended to be operated with facility and safety for children, which shall be simple, economical and practical and meeting all the peculiar requirements of a device adapted for such purposes. At the same time the completion of such invention has involved certain features which are not necessarily exclusively applicable to a miniature article of this character, but may be applicable to other sizes, forms and structures.

In part my invention has to do with automobiles for children, which are self-propelling, and means thereon to enable a child to control the application of the power in a manner best adapted to avoid the possibility of accident, also features of construction intended to enable the manufacture of such vehicles at a minimum of cost; while one form of the embodiment of my invention relates particularly to the application of improved spring supplied power and its adaptation in various features to efficiently, uniformly and advantageously propel the vehicle; in addition to which other details of construction are included in my invention with their respective advantages which will appear from more detailed description hereinafter.

In the drawings accompanying the specification is shown a vehicle propelled by the unwinding of a spring or springs, while the particular methods of control and arrangement of the structure are applicable to vehicles for the same general purpose, in which other sources of power may be readily used. For the use of children it has appeared most important that the control of such a vehicle be simple and that any means for putting the vehicle into operation or applying the power, should be of such a character as to operate only under

continued attention of the child, in view of which I have devised means whereby the driving effort will immediately cease, except upon the continued close attention and correct understanding of operation by the child, and in which the power will be thrown out immediately should the child, for instance, fall from the vehicle or become inattentive and move its feet or hands, as the case may be in any particular structure. In this respect a feature of safety control is automatic, making the operation of the vehicle automatically possible only in case of proper understanding on the part of the child.

With the recent great development of internal combustion engines and their simplification and reliability, as well as the possibilities of other sources of power, such are readily applicable to a vehicle in combination with my details of construction of control and arrangement for propulsion, while in the form hereinafter particularly shown and described I have embodied a particular arrangement of springs and automatic means for gaining uniformity of discharge of power from such spring storage.

In the further development and construction of varying sizes of articles in accordance with my invention it will be seen that many of the combinations and features become applicable to larger vehicles and in this respect it is not my intention that such should be limited necessarily to a miniature or child's automobile, but that they are broadly applicable as hereinafter claimed by me.

In the drawings,—

Figure 1 is a side elevation of a toy automobile, with certain parts broken away to show the internal construction.

Fig. 2 shows the attaching means of the ends of the springs to the driven member illustrating one form of means for unifying the torque.

Fig. 3 shows in detail a power controlling means.

Fig. 4 is a side view of a vehicle showing a modified form of power transmission mechanism.

Fig. 5 is a plan view of a vehicle showing modified arrangement of power storage and power control.

Fig. 6 is a side elevation of a vehicle showing suitable arrangement for power storage by spiral band spring and means of control and winding.

The particular form of my invention shown, as, for instance in Figs. 1, 2 and 3 comprises a frame or body A with a suitable seat or box B, and mounted on the forward part of the vehicle a nest of coil springs C the axis of which is longitudinal of the vehicle. These springs are attached to a winding plate C' and at their rear end connect by intermediate devices to the driven plate C² to which is attached a gear D driving a small pinion d on the longitudinal shaft E which by means of bevel gear e drives a bevel gear e' on the rear axle and transmits power to the driving wheels F.

The winding plate C' embodies or is affixed to a gear c which is actuated by a pinion c' operated by a crank c². A ratchet connected with the pinion c' with suitable pawl and spring serves to lock the pinion and consequently the crank against backward movement or reverse driving.

Attached to the driven plate C² or gear D is a plurality of radial threaded rods G embodying lugs g to which the ends of respective springs are attached. Attached to the gear D or the driving plate is a brake drum H surrounded by a brake band h which is suitably connected to an operating pedal or other lever j located conveniently for application of pressure by the foot of the occupant. On the inner ends of the radial rods G are attached pinions g' which engage a common pinion g² fixed to a shaft K projecting axially through the nest of springs C and supported in a front bearing k and a rear bearing k² suitably supported on or near the dash of the vehicle, and carrying near the rear bearing the hub k³ for supporting the driven plate C² or the driven gear D.

Cushion B² is normally held upward from its seat by spring b, and is connected by link b' to one end of lever b² suitably pivoted to the body of the vehicle, the other end of lever b² connects by link b³ to the horizontally extending arm of bell lever f, the vertically depending arm of which is linked to the lower end of lever m suitably mounted in the chassis. The upper end of lever m is cut out so as to notch under and lock the end of pedal j, which is normally held in its upward position by spring j', and prevents the accidental downward movement of said pedal which would start the vehicle in motion.

Upon the occupant seating himself in the vehicle, cushion B² is depressed and through the system of links and levers above described, the latch or lever m is withdrawn from beneath the pedal j, thus allowing the

operator to deflect said pedal by foot pressure or otherwise, to start the vehicle in motion.

Having enumerated most of the co-operating parts of a structure embodying my inventions, the operation of the particular form shown will be understood as follows:

In view of the increased purchase owing to the difference in the size of pinion c' and winding gear c, the proportions are made so that the limited power of a child can turn the crank c² and thereby turn the winding gear c. The ratchet c³ will prevent back-flying of the crank, and the continued operation by the child will coil up or in other words wind the nest of springs C putting them in tension, thereby storing power. During this operation the shaft K turns in the same direction as the winding plate C' being rigidly attached thereto and thereby turns the small bevel gear g² which in turn rotates by means of the small bevel gear g' the radial rods G. This action results by suitable threading on the rods in drawing toward the center all of the spring attaching lugs g with the result that when the spring has been completely wound up the ends thereof attached to the driven plate C² or to the gear D will be acting thereon at the minimum predetermined radius. This exists when the springs are in greatest tension producing the condition of greatest spring tension operating on the smallest radius within the limits of the design. While this winding has been in progress a suitable spring j' has kept the pedal j in a position which by any usual form of toggle or bell crank connection actuates and causes brake band h to firmly clamp the brake drum H and prevent the driving gear D from rotating.

The operator now entering the vehicle and being prepared to start, applies pressure to the pedal j thereby releasing the driving gear D and the tension in the springs acts to unwind them thereby driving the gear D which turns the small pinion d driving the shaft E and the rear gears e and e' thereby propelling the vehicle. As the spring unwinds the shaft K being stationary with its small bevel pinion g², the unwinding of the driven disk C² carrying with it the radial rods G, the latter are caused to turn by the pinion g' at their inner ends and gradually project the spring attaching lugs g radially outward, substantially in proportion to the degree of unwinding of the springs. This results in the application of the spring tension to a constantly greater radius as the point of application to the driven disk moves steadily outward during the unwinding, in view of which as this spring tension lessens and the radius increases, a proper diminishing of the respective parts causes a substantially uniform application of driving effort or

- 5 torque to the driven disk C² or the gear D, within reasonable limits of spring discharge. In this manner it is possible to very largely eliminate the excessive power which would otherwise come into action immediately upon the releasing of the spring under high tension and will consequently effect a uniform delivery of power during a large range of discharge of power from the spring.
- 10 5 This method of unifying the discharge of a spring, either coiled or other form, has been intended by me for use in other devices, as for instance, clock actuating mechanism, when a very large spring is desired for driving power for a long period. It will be seen that many modifications of the form of application of the spring discharge connections may be made without departing from the spirit of my invention.
- 15 20 In the vehicle shown I embody in addition to the parts already specified, steering wheels L with link connections l to a pillar l' and a hand wheel or other suitable operating device L². A lever M located close to the occupant's seat may be used with suitable connections to clutch or unclutch the driving gear e' from the axle of the driving wheels F. By such arrangement it is possible for the driver to clamp or lock 25 the discharge gear D when going down hill and save power, while permitting the vehicle to coast free from any connection of the driving gear system. A second foot pedal N by suitable connections as rod n and brake arm n' and brake shoes n² enables the operator to apply brakes to the rear wheels of the car when the clutch is out of connection or otherwise.
- 30 35 As shown in Fig. 4, a pulley D takes the place of a gear and a driving cord or belt O passing around the pulley and around sheaves or idlers o, encircles a pulley O' on the rear axle, effecting driving of the vehicle in a simplified form.
- 40 45 In Fig. 5, it will be seen that the spring storage is located underneath the driver's seat, by which arrangement the gear P driving a gear or belt p actuates the rear axle through the clutch p' moving on a spline on the rear axle so that the same member can be thrown out of engagement when the spring mechanism is locked against discharge, and move a clutch q into engagement with a clutch member Q fixed to the vehicle or against rotation. The clutch q and clutch member Q serve to retard or stop the vehicle when coasting or otherwise running, when the driving mechanism is out of gear.
- 50 55 60 In Fig. 6 is shown arrangement of band spring R in a box or the main body portion of the vehicle, which is particularly suitable in some cases where large storage space for such member is desired; in such a structure the winding is effected by means of bevel gears r and shaft r' actuated by a crank r². In this structure I find a very practical driving arrangement comprises the disk S attached to the rear axle engaged by a friction wheel s driven by the shaft s' 70 which in turn is driven by a pulley or gear s² actuated by the driving member T actuated by the unwinding of the spring R. By this means it is always possible to obtain a very simple driving control by shifting the pulley s to greater or less radial distance from center of the disk S by any suitable means, as for instance, bell crank U operated by the rod u and controller handle u'. In view of the light weight of machines of this character and their intended use on smooth, hard surfaces, and their light load, a very small amount of power is necessary to propel them and with small internal friction they will to a very large extent coast or move with so little power as to make a detachable speed mechanism desirable, so that the tension of the spring can be conserved as much as possible and utilized only when inclines are reached. The arrangement 80 shown in Fig. 6 in this respect becomes most desirable.
- 65 70 75 80 85 90 95 100 105 110 115 120 125 130 Having now fully described the particular forms of my invention I direct attention to the important features of control when my inventions are embodied in a vehicle for use by children. Among these it will be observed that whether the power for propelling the vehicle is spring or, as has been stated, may be an internal combustion engine or any desired suitable source, by the use of my controlling method, the vehicle will not be moved, except close attention is paid by occupant, and constant attention, by applying or actuating a lever, and on the other hand any inattention of the driver, such as permitting his foot to slip or moving his hand when such control is by a hand lever, will result in automatically cutting off the power from driving the vehicle.
- 110 115 120 125 130 While the use of spring stored power has its well known limitations, it will be seen that by my method a uniform discharge or application of the power is made possible, thereby bringing such spring propelled propulsion within the range of practical utility. I have found that with the increased use of self-propelled vehicles, many cases arise where the distance to be covered is very small, even outside of the use for children's vehicles, and in some such cases it is practical to utilize even a large vehicle with properly controlled spring power storage. The advantage of regaining practically all of the stored energy in a properly constructed and properly propelled spring affords the opportunity of practical use of such an arrangement for particular cases. In such events I arrange for the winding up of the springs by any suitable stationary power

supply, as for instance, by coupling to an electric motor and having a large speed change between the winding shaft and the spring drum disk. A vehicle so constructed can be used particularly for short runs and level roads, as for instance, in numerous localities where well built board walks, convention halls or the like, have now become common. In such application of the various features of my invention or embodiment of their combinations, advantages are offered over the now usual methods of self-propulsion of vehicles, in that the danger of fuel, or the acid incident to the use of batteries, or the weight of electric storage batteries, are eliminated.

While larger size machines for children may be operated by internal combustion engines, using some of the features of my invention, the smaller sizes are found desirable to propel by springs only, and in so doing avoid any objectionable features which otherwise would be involved and would be dangerous for very small children, when for instance, acids, oils, inflammable material and grease, etc., were present. For these very small vehicles the elimination of any substantial amount of power or otherwise dangerously regarded adjuncts, permits their use on side walks, whereas otherwise they would have to be classed with the usual self-propelled vehicles and relegated to the roadways, obviously making their use by small children impossible or precarious to a practically prohibitive degree.

While I have shown particular forms of embodiment of my invention and have described such and also various applications and modifications thereof, my invention is not confined to such particular forms shown and described, or their particular combinations specifically recited, but what I claim and desire to secure by Letters Patent is:

45 1. In a self-propelled vehicle, a spring for storing energy, means for putting said spring in tension and automatically holding the same, means for normally locking said spring against unwinding, a device accessible to the occupant when in the vehicle for releasing said spring and permitting its unwinding upon the continued actuation of said device, means for locking said device in inoperative position, released only by the weight of the occupant acting on the seat of the vehicle.

2. In a vehicle, a spring for storing power and means operating on one end of said spring for putting the same in tension, a driven means connected to the other end of said spring, means connected to said driving means to automatically lock said spring against unwinding, connections with said driving means for transmitting the unwind-

ing of said spring to propel the vehicle, an operating device normally holding said connections with said driving means in inoperative position, means for locking said device released by the weight of the occupant on the seat of the vehicle.

3. In a vehicle, springs for storing power, means for holding one end of each of said springs against rotation and means connected with the other end of said springs whereby the force of unwinding is automatically applied at a varying radius on the driven mechanism of the vehicle in proportion to the degree of tension in the spring and means for transmitting the stored power to the driving wheels, means for controlling said transmitting means and a locking device therefor, said device being released only by the weight of the occupant on the seat of the vehicle.

4. In a self-propelled vehicle, a plurality of springs for starting power and driving said vehicle, means for unifying the torque of transmission of said vehicle, means for controlling the transmission of power and a device for locking said means in inoperative position released only by the weight of the occupant on the seat of the vehicle.

5. In a self-propelled vehicle, a plurality of springs to drive said vehicle, means for automatically varying the radius of application of the distending ends of said springs, means for locking the opposite ends of said springs against rotation and means for winding them in one direction and locking them at said end, means for controlling the unwinding by a pedal requiring continued application to release the unwinding, and a device for locking said pedal except upon application of the weight of the occupant on the seat of the vehicle.

6. In a self-propelled vehicle, driving springs in the front of said vehicle disposed about a longitudinal shaft, means at the forward end of said shaft for winding said springs, a casing inclosing said springs and winding mechanism and driving mechanism, and a crank projecting beyond said casing to operate said winding mechanism, driving mechanism connected to the rear end of said springs and gearing connecting said driving mechanism to the driven wheel of the vehicle, a seat in the rear of said vehicle, and steering mechanism and driving mechanism released in operative position accessible to the occupant on the said seat, means operated by the weight of the occupant on the seat to permit the actuation and release of the driving mechanism.

7. A toy automobile having a seat in the rear and a nest of coil springs in forward end, a hood completely inclosing said springs, winding mechanism at the forward end of said springs operable from without

the casing, driving mechanism at the rear end of said springs, interlocking mechanism to normally prevent the unwinding of the spring at the rear to drive the propelling mechanism, interconnected, whereby the vehicle is locked against propulsion when the weight of the driver is released from the seat, a brake, steering and drive release de-

vice accessible to and operable by the occupant when on the seat.

Signed at New York, this 11th day of December, 1908.

HERMANN F. CUNTZ.
